COLLAPSIBLE IRONING TRAY

Harriett Herman Tiegs, Gardena, Calif.

Application October 27, 1948, Serial No. 56,883

7 Claims. (Cl. 38—111)

1. This invention relates to an ironing board, and

more particularly to a collapsible tray adapted to be attached to an ironing board.

The principal object of the invention is to provide a collapsible tray adapted to be attached to an ironing board for supporting articles being ironed, to prevent the articles from dragging on the floor and becoming soiled.

Another object of the invention is to provide a collapsible tray adapted to be attached to an ironing board for supporting articles being ironed, which will eliminate the tension or pull caused by the hanging ends of the articles.

A further object of the invention is to provide an ironing board with a tray which can be extended when needed and can be collapsed when not needed, and either compactly folded beneath the ironing board, or can be disengaged from the ironing board and stored in a small space.

Still another object of the invention is to provide an ironing board with a collapsible tray which is extremely simple and inexpensive to manufacture.

Other objects and advantages will be apparent during the course of the following description.

In the accompanying drawings forming a part of this application, and in which like numerals are employed to designate like parts throughout the same:

Figure 1 is a side elevational view of an ironing board provided with the collapsible tray, according to the present invention;

Figure 2 is a sectional view taken on the line 2—2 of Figure 1;

Figure 3 is a view illustrating the tray in collapsed position;

Figure 4 is an enlarged fragmentary elevational view, with parts broken away and in section, of the tray;

Figure 5 is a bottom plan view of the upper portion of the assembly for attaching the tray to the ironing board;

Figure 6 is a sectional view taken on the line 6—6 of Figure 5;

Figure 7 is a front elevational view of the upper portion of the assembly for attaching the tray to the ironing board;

Figure 8 is a rear elevational sectional view of the lower portion of the assembly for attaching the tray to the ironing board;

Figure 9 is a sectional view taken on the line 9—9 of Figure 4.

Referring in detail to the drawings, the numeral 10, Figure 1, designates a conventional ironing

board provided with pivotally connected legs 11 and braces 12.

Secured to the bottom of the ironing board 10 by screws 13, Figures 5 and 6, is a bracket 14 having inwardly-curved ends 15 for slidably receiving a tongue or plate 16. Secured to flanges 17 on the plate 16 by rivets 19 is a U-shaped support embodying a pair of vertically-disposed, spaced, parallel standards 18. Arranged in side-by-side relation with respect to the standards 18 and mounted for vertical sliding movement therealong is a pair of spaced, parallel, vertically-disposed arms 20. A manually-operable thumb screw assembly 22 is mounted in embracing relation with respect to the arms and standards, Figures 1 and 7, and the thumb screw assembly 22 can be loosened or tightened in order to either permit vertical adjustment of the arms 20 or to maintain the latter immobile. Secured to the lower end of each of the standards 18 by rivets 23 is a tubular casing 24 which slidably embraces the adjacent arms and serves as a guide to maintain the standards and arms in alignment.

The lower ends of the arms 20 project through a pair of spaced slots 25, Figures 8 and 9, formed in the top of a bracket 26 and the arms 20 are each pivotally connected to the sides of the bracket 26 by rivets or pins 27, so that the arms are pivotally connected to the bracket 26 for permitting the arms to be folded against the tray for storage. The bracket 26 is provided with a pair of opposed flanges 28 to the upper semi-circular plate 29 of a housing 30.

The housing 30 embodies the upper plate 29 and lower semi-circular plate 31, Figure 4, arranged in spaced, parallel relation therebelow. A plurality of pins 32 and spacer blocks 33 extend through the plates for maintaining the latter in spaced, assembled relation. Interposed between the plates 29 and 31 and projecting therefrom is a plurality of tubular staves or rods 34 having their outer ends bent upwardly. A rivet 35 extends through the plates 29 and 31 and through each of the staves 34 to thereby provide a pivotal connection between the staves and the plates, so that the staves 34 can be moved to collapsed (Figure 3) or extended position (Figure 2). A suitable webbed cover 36, fabricated of suitable cloth, is provided with a line of stitching 37 and a plurality of pockets 38 for receiving the individual staves 34, so that the cover 36 will be supported on the projecting ends of the staves 34 and define a tray-like member. The upwardly-bent ends of the staves 34 urge the

outer edges of the cover 36 upwardly to form an upwardly-extending rim for preventing articles from accidentally falling off of the cover.

In use, the device when needed may be releasably attached to the ironing board 10 by sliding the tongue 16 into the bracket 14 and the user can adjust the space between the collapsible tray and the ironing board by adjusting the thumb screw assemblies 22. The staves 34 are pivoted about the pins 35 to their extended position, Figure 2, and the attachment will support the ends of articles being ironed to prevent the articles from dragging on the floor and becoming soiled. The weight of the collapsible tray is centered near the center of the ironing board, which prevents the ironing board from tipping over. Also, the user can iron from either side of the ironing board by collapsing or moving the section not needed into an out-of-the-way position.

As many embodiments may be made of this inventive concept, and as many modifications may be made in the embodiment hereinbefore shown and described, it is to be understood that all matter herein is to be interpreted merely as illustrative and not in a limiting sense.

I claim:

1. In an attachment for ironing boards, a bracket secured to the bottom of said ironing board, a plate releasably mounted in said bracket, a pair of spaced parallel vertically-disposed standards dependingly carried by said plate, arms arranged in superposed relation with respect to each of said standards and slidably connected to the latter, a housing carried by the lower ends of said arms, a plurality of staves pivotally connected to said housing and projecting from the latter, and a cover carried by the projecting ends of said staves.

2. In an attachment for ironing boards, a bracket secured to the bottom of said ironing board, a plate releasably mounted in said bracket, a pair of spaced parallel vertically-disposed standards dependingly carried by said plate, arms arranged in superposed relation with respect to each of said standards and slidably connected to the latter, a housing carried by the lower ends of said arms, a plurality of staves pivotally connected to said housing and projecting from the latter, a cover carried by the projecting ends of said staves, and manually-operable means for maintaining said arms immobile with respect to said standards.

3. In an attachment for ironing boards, a bracket secured to the bottom of said ironing board, a plate releasably mounted in said bracket, a pair of spaced parallel vertically-disposed standards dependingly carried by said plate, arms arranged in superposed relation with respect to each of said standards and slidably connected to the latter, a housing carried by the lower ends of said arms, a plurality of staves pivotally connected to said housing and projecting from the latter, a cover carried by the projecting ends of said staves, and manually-operable means embodying a pair of thumb screws for maintaining said arms immobile with respect to said standards.

4. In an attachment for ironing boards, a

5 bracket secured to the bottom of said ironing board, a plate releasably mounted in said bracket, a pair of spaced parallel vertically-disposed standards dependingly carried by said plate, arms arranged in superposed relation with respect to each of said standards and slidably connected to the latter, a housing carried by the lower ends of said arms, a plurality of staves pivotally connected to said housing and projecting from the latter, and a cover carried by the projecting ends of said staves, said housing being pivotally connected to the lower ends of said arms.

10 20 25 30 35 40 45 50 55 60 65 70 75 80 85 90 95

5. In an attachment for ironing boards, a bracket secured to the bottom of said ironing board, a plate releasably mounted in said bracket, a pair of spaced parallel vertically-disposed standards dependingly carried by said plate, arms arranged in superposed relation with respect to each of said standards and slidably connected to the latter, a housing carried by the lower ends of said arms, a plurality of staves pivotally connected to said housing and projecting from the latter, a cover carried by the projecting ends of said staves, and manually-operable means for maintaining said arms immobile with respect to said standards, said housing being pivotally connected to the lower ends of said arms.

6. In an attachment for ironing boards, a bracket secured to the bottom of said ironing board, a plate releasably mounted in said bracket, a pair of spaced parallel vertically-disposed standards dependingly carried by said plate, arms arranged in superposed relation with respect to each of said standards and slidably connected to the latter, a housing carried by the lower ends of said arms, a plurality of staves pivotally connected to said housing and projecting from the latter, a cover carried by the projecting ends of said staves, and manually-operable means embodying a pair of thumb screws for maintaining said arms immobile with respect to said standards, said housing being pivotally connected to the lower ends of said arms.

7. In an attachment for ironing boards, a first bracket provided with inwardly-curved ends secured to the bottom of said ironing board, a plate slidably arranged between said curved ends, a support embodying a pair of vertically-disposed standards dependingly carried by said plate, arms arranged in superposed relation with respect to each of said standards and mounted for vertical sliding movement with respect to the latter, a manually-operable thumb screw assembly connected to said standards and arms for maintaining the arms immobile in their adjusted position, a casing secured to the lower end of each of said standards and slidably receiving the complementary arm for guiding the latter, a second bracket pivotally connected to the lower ends of said arms, a housing embodying a pair of spaced parallel semi-circular plates dependingly carried by said second bracket, a plurality of staves pivotally arranged between the plates of said housing and projecting out of the latter, and a cover provided with a plurality of pockets for receiving the projecting ends of said staves.
